UNITED STATES PATENT OFFICE

2,630,234

COLLAPSIBLE CONTAINER

Erwin Zellweger, Zurich, Switzerland

Application November 15, 1950, Serial No. 195,721

1 Claim. (Cl. 217—48)

1

The present invention relates to a collapsible container, for example a packing case, the four walls of the container being hinged together at their adjoining edges.

The container according to the present invention differs from known types of such collapsible containers in that a removable bottom is provided, which can be pushed along in guides formed on sides of the container lying opposite each other, these guides having at one place a cavity and the bottom at the corresponding place a projection, the whole in such a way that the bottom with the projection, when the bottom is pushed in, enters into the cavity under the influence of its inherent elasticity, the bottom and the container being thus secured in the position of use.

One example of execution of the subject of the invention is illustrated by way of example in the accompanying drawing, where:

Fig. 1 shows a perspective view,

Fig. 2 a partial longitudinal section along line 2—2 of Fig. 1,

Fig. 3 a view looking down on the collapsed container, and

Figs. 4 and 5 are sections on the lines 4—4 and 5—5 respectively of Fig. 2.

The side walls of the illustrated container are formed of boards 1 and the front and rear walls of boards 1'. The adjoining edges of the boards 1 and 1' are provided with projections 4 engaging with each other. These projections are bored through vertically and this bore takes a metal rod or wire 2. The ends of this rod are widened out to form a head, thus preventing the rod from falling out. In this manner the walls of the illustrated packing case are hinged together, so that the walls of the container can be laid together into the position shown in Fig. 3. For closing the container below and for securing it in the position of use as shown in Fig. 1, a bottom 3 is provided, which can be secured in its position of use by special means, still to be described. For this purpose a bottom batten 8 is secured to and along the lowermost board 1 of each side. Battens 8 project inwardly with their portions 9 to form guide ways for the bottom 3. In the middle of each of the battens 8, a short piece of the portion 9 is cut away so as to form a recess 7 and the portion 9 between the recess 7 and the front wall is forwardly inclined as clearly shown at 18 in Fig. 2. In the planes of the front and rear walls, transverse slats 10 and 11 are secured to the ends of the battens 8 so that slots 12 and 13 are formed between the

2

lowermost boards of the front and rear walls and the slats 10 and 11 respectively. The illustrated bottom consists of separate boards running longitudinally, which are connected to each other by transverse battens, namely a front batten 5, a median batten 6 and a rear batten 5'. The width of the bottom is such that it fits between the side walls of the container, and the thickness of the bottom and that of one of the battens 5 and 5' together is such that the bottom ends with the battens fit into the slots 12 and 13, respectively. The batten 6 functions as securing batten, to secure the bottom in the position of use. Whereas the length of the battens 5 and 5' is shorter than the width of the bottom 3 so as to fit between the legs 9 of the battens 8, the length of the batten 6 is approximately equal to that width, and the width of that batten is approximately like that of the recess 7. However, as it can be seen from Fig. 5, the ends 14 of the securing batten 6 are kept thinner in the neighbourhood of the guide ways 18 than between the two battens 8. The bottom 3 may be inserted by passing its rear end through the front slot 10 and pushing it to the rear wall. When batten 6 has passed this slot, the thinned ends 14 will slide on the guide ways 18, the bottom 3 being then somewhat inclined down. As soon as the thinned ends of the batten 6 arrive in the neighbourhood of the recesses 7, they will spring into the latter. Simultaneously the battens 5 and 5' will engage in the slots 12 and 13, respectively. In this way the bottom is secured in the position of use. In order to remove the bottom from this position, it is sufficient to press it up a little and to raise the thinned ends of the batten 6 out of the cavities 7. When the described packing case is in use, the bottom is secured in the position of use by the goods within the case, since the latter tend to press the thinned ends of the batten 6 into the cavities. In the described manner, securing of the collapsible container in the position of use is ensured with simple means and consequently in an inexpensive way.

45 What I claim is:

A collapsible container comprising two side walls, a front wall and a rear wall, each side wall being hinged to said front and rear walls, said front and rear walls being provided with transverse slots near the lower edges of said walls, a removable bottom fitting between said side walls and with its front and rear ends into said slots respectively, guide rails for said bottom along said side walls between said slots, said rails being provided each with a recess substantially in the

middle of their length and being downwardly inclined from said recesses to said front wall and said bottom including on its lower surface three transverse battens, one of said battens substantially in the middle of said bottom and the other ones at the ends of the bottom respectively, the ends of the first one of said battens being of a smaller thickness than said other battens and engaging said recesses when said ends of said bottom with said other battens are in engagement with said slots, respectively, and said other battens complementing the thickness of said bottom substantially to the width of said slots.
